FORMING DIE SET

Augusto De Rentis, Prospect Park, Pa.

Application September 13, 1940, Serial No. 356,629

4 Claims. (Cl. 153—34)

(Granted under the act of March 3, 1883, as
amended April 30, 1928; 370 O. G. 757)

The invention described herein may be manufactured and used by or for the Government for governmental purposes, without the payment to me of any royalty thereon.

This invention deals with an improvement in the manufacture of escapement levers for time shell fuse clockwork which consists in reforming the escapement pallets after manufacture of the same and prior to assembly in the clockwork. The dimensions and degree of relative orientation of the parts of the lever are of vital importance in the proper functioning of the clockwork. The pallets, in particular, which include the points of contact with the escapement wheel are of a relatively small dimension and small variations in the distance between such points of contact will introduce large errors in the timing. During manufacture the escapement levers, due to various causes, notably nesting, will suffer deformation between the pallets, causing a change in this vital dimension. In the present invention such difficulties are avoided by a check step which will reform the pallets prior to assembly in the clockwork.

It is, therefore, an object of this invention to reform an escapement lever for the clockwork of a time shell fuse subsequent to fabrication of the lever and prior to its assembly into the fuse.

In a preferred embodiment of the invention, this object is accomplished by means of machinery, including forming dies as illustrated in the accompanying drawings, in which:

Fig. 1 is a front elevation in section of the machine, with the escapement lever in place, showing the reforming step completed.

Fig. 2 is a plan view on the line 2—2 of Fig. 1; Fig. 3 is a partial sectional view on the line 3—3 of Fig. 1;

Fig. 4 is a detail of the side forming dies;

Fig. 5 is a bottom plan of the upper outer die;

Fig. 6 is a bottom plan of the stripper; and

Fig. 7 is a view in perspective of an oscillating lever of the type to be reformed.

Following is a detailed description of the drawings and of the manner in which the invention is to be practiced:

In Fig. 7, which shows an oscillating escapement lever, 1 is the central hole in which the bearing pivot is to be fastened, 2 and 3 are the pallets with knife edges 4 and 5, respectively, for engagement with an escapement wheel.

Referring to Fig. 1, the end of rod 6 on piston 7 is maintained above the level of anvil 8 by the pressure of spring 9. Rod 6 is a centering device for the work, in this case for receiving

the central hole 1 of the escapement lever of Fig. 7. For disengaging the work, rod 6 is withdrawn by action of hand lever 10, pivoted about bolt 11.

Plate 12 (Fig. 2) serves to hold the escapement lever in its proper clock-angle orientation on the bed plate 13 by means of notch 14.

Four dies are employed in the reforming operations, two vertical dies 15 and 16 which will be referred to as the upper outer die and upper inner die, respectively, and two side dies 17 and 18.

The press head for the dies consists of two parts 19 and 20 joined by bolts 21 and 22. 23 is a dowel. The thrust is transmitted from auxiliary machinery (shown generally at 24) through the head and thence to the upper dies by means of a spring 25. The upper outer die has a sliding fit in head 20 and is held against rotation by key 26 fitting in slot 26'. The downward motion of head 19, 20 also impels the side dies 17 and 18 inward by the action of rollers 27 and 28 on cam surfaces 29 and 30, respectively. The travel of the side dies is regulated by set screws 31 and 32. On raising the press head, the side dies are returned by springs 33 and 34, such motion being limited by set screws 31' and 32'.

The upper inner die 16 is clamped within the upper outer die 15 by means of a set screw 35 and the two dies move as a unit. The inner die moves to a position within the pallets and serves as a mandrel for the pressing or reforming operation of the side dies. The upper outer die 15 is brought down on the arms of the escapement lever as shown by the dotted lines in Fig. 1, and holds them flat on the bed plate during the reforming operation. This outer die (Figs. 4 and 5) has slots 36 and 37 and sectors 38 and 39 to accommodate the pallets, side dies and stripper fingers. The latter are shown at 40 and 41 in Figs. 1 and 6.

The stripper 42 is a sleeve enveloping outer die 15 and undersliding it by means of fingers 40 and 41. These fingers are designed to engage the tops of pallets 2 and 3 and remove them from the upper dies in case they adhere thereto. The fingers are prevented from contacting the pallets prior to ascent of the upper dies, by the adjustment of stop 43. On the down stroke of the press, rod 44 engages the stop and spring 45 is slightly compressed. The stripper 42 is connected to rod 44 by means of a yoke 46 engaging in a necked portion 46' of the stripper and is therefore brought to a stop with rod 44. On ascent of the dies, spring 45 will cause

stripper 42 to lag behind the press head and come into engagement with pallets 2 and 3 in case they have adhered to the upper dies, and will thus remove them therefrom.

The upper dies are connected to the press head by spring 25 because they must be brought into position over the escapement lever in advance of the contact with the pallets by the side dies, otherwise a jamming action would occur.

The operation is as follows. Hole 1 of the escapement lever is slipped over rod 6 and one arm of the escapement lever is slipped into notch 14. The upper dies are brought down into contact with the work and at the same time, side dies 17 and 18 move in and press the pallets 2 and 3 into their proper position, in this case perpendicular, with respect to the plane of the lever arms. It may be necessary to make the upper inner die of a diameter somewhat smaller than the inner diameter of the pallet sectors and also to shape the pressure area of the side dies so that the top part thereof contacts the pallets in advance of the lower part in order that the pallets will assume the desired final position after their natural resilient restoring force has expended itself following the reforming operation.

On the up stroke of the press the side dies retract. If the work has adhered to the upper dies it is removed therefrom by the stripper. Lever 10 is pressed down and the work is easily brushed from the bed plate. Lever 10 is released and another piece of work inserted on rod 6 to commence another cycle.

The particular machine described herein is for the purpose of illustration only and it is not intended that the invention be limited thereby, but only in such degree as lies within the scope of the appended claims.

I claim:

1. A machine for reforming escapement levers for clockwork fuses, said levers having pallets bent at an angle to the plane of the lever proper, said machine comprising a bed for reception of the lever, a resiliently held reciprocating anchoring rod for the lever, a slotted member on the bed to receive one arm of the lever to position the same, a head member bearing a vertical die for pressing on the face of said lever, transverse dies on said bed to engage said pal-

lets, cam means on said transverse dies, and cooperating means on said head member to transmit its motion to the transverse dies through said cam means.

5 2. In a machine as in claim 1, a sliding fit of limited motion between said head member and said vertical die and resilient means normally holding said vertical die in an advanced position with respect to the motion of said head member.

3. In a machine as in claim 1, stripper means carried by said head member and resiliently held for limited motion adjacent said vertical die for removing adhering levers therefrom.

4. A machine for reforming escapement levers for clockwork fuses, said levers having pallets bent at an angle to the plane of the lever proper, said machine comprising a bed to receive the lever, a spindle mounted in said bed for reciprocal motion into and out of engagement with a central hole in said lever and spring means to hold the spindle in said engagement, manual means for operating said spindle, receiving means on the bed for a portion of said lever to hold the same in proper orientation, a press head for reciprocal motion to and from said bed, a vertical ram in said press head for engaging said lever to hold the same against the bed, said ram being mounted in said head for limited reciprocal motion, spring means above said ram to hold the same normally extended, a collar around said ram and slidable thereon, fingers on said collar positioned to sweep the end of the ram to remove adhering levers therefrom,

35 a shaft slidable within limits in said press head and carrying said collar, spring means holding said shaft normally extended, stop means on said bed to engage said shaft and thus raise the collar on the ram above the end of the ram

40 when the head is lowered, transverse die members slidable on said plate against spring pressure to engage said pallets in pressing engagement, means on the ram fitting within the pallets to form a mandrel for the pressure of the transverse dies, cam means on said transverse dies, depending legs on said press head, and means on said legs to engage said cam means and actuate the transverse dies.

50 AUGUSTO DE RENTIIS.
